CIGAR WRAPPING MACHINE

Ernst Hermann Jähne, Dresden, Germany, assignor, by mesne assignments, to J. C. Muller N. V., Rotterdam, Netherlands

Application October 8, 1936, Serial No. 104,654
In Germany October 21, 1935

6 Claims.

(Cl. 93—2)

This invention relates to cigar wrapping machines and has for its object to provide a machine in which the completed cigars may be provided with an outside band or two without the manual handling of such cigars. In place of the cigar band, a band such as is used in certain countries known as a customs house band or a tax band, may be applied.

The principal object of the invention is to provide a machine which is in continuous operation and which step by step leads the article to be handled from one place of operation to another automatically through the machine. A further object is to produce a machine which runs smoothly, efficiently, and quietly with a speed commensurate with a fair and profitable production.

For this purpose, the invention embodied in the structure hereinafter to be described consists in controlling the cigars and allowing none of the same to escape such control so that they may be passed through the machine in order that a band may be placed thereon and thereafter subject such band to a suitable pressing action to cause adhesive, if used, to firmly hold the band around the cigar. The cigar with the band thereon is then preferably conducted by being held at its ends for the next stage of operation, which may be another presser or two, or may be another station for applying a second band, until the cigar is completed, when it is ready to be discharged from the machine.

To carry out this invention, a cigar-holding device is provided which holds the cigar at its ends by means including a sponge-rubber-insert in a rail device or holder, and which cigar-holding device is moved longitudinally of the machine to convey the cigar from its initial position to the various stages of operation to which it is subjected. Combined with this cigar-advancing means, other means is provided which acts by means of a suction member to take out of a conveyer the wrapper or the band and place the same in position over the cigar at the proper time. In addition, mechanism is provided in order to fold the wrapper or wrap the same over the cigar filler in one case or over the wrapped filler in the other case so that in the case of the latter the cigar is provided with two wrappers. This mechanism is characterized essentially by the fact that a swinging movement of the member is utilized in order to press that portion of the wrapper which overlies the sides of the cigar filter down and under the same. Rail-like holders which grip the ends of the cigars and

which are parallel with each other, move toward each other to hold the cigar, and away from each other to release themselves from the cigar and have for their object to advance the cigar in the machine and then to return to their initial position. A plurality of such gripping fingers or holders are provided longitudinally of the machine so as to advance the cigar step by step to be wrapped or pressed. Between the two apparatuses used for the folding or wrapping of the wrappers over the cigar, the intervening space is used for provision of presser members to press the wrapper securely against the filler, and such arrangement permits the operation of the machine in a manner so as to provide a relatively short path for each stage of operation and in consequence an increase in working speed of the machine, and at the same time a quiet method of operation is obtained.

A further object of the invention consists in supplying the cigar fillers to the machine itself by suitable means and thereupon holding a group of cigars which are positioned foremost, excepting the end cigar. Said end cigar is then taken hold of by the gripper or cigar holders after having been released, and while this action takes place a retarding action prevents the further feeding of the cigar fillers to the machine. When the very end cigar has been released and removed the braking action is released and a friction pad which holds a group of end cigars, is raised whereby the next cigar may be fed forward to be operated upon in like manner. For this purpose, the invention consists of a machine in which there is a step-by-step forward movement of a cigar filler which is to be wrapped by first holding the same and then releasing it and then moving it into position where a wrapper is superposed, then folding the wrapper around the cigar filler, then moving the wrapped cigar to one or more pressure devices and then, if desired, providing a second wrapper by means similar to the first wrapping means, the cigar in these various stages being moved by parallel holders supplied by suitable sponge rubber so as not to injure the cigar ends and until after the final wrapping and the cigar is discharged from the machine.

The invention will be further described, an embodiment will be shown in the annexed drawings, and the invention finally pointed out in the subjoined claims.

In the accompanying drawings—

Figure 2 is a vertical cross section of the same taken on line II—II of Fig. 1;

Figure 3 is a detailed view of the end of a cigar and a sectional view of one of the cigar end holders;

Figure 4 is an enlarged full showing of the device shown diagrammatically in Figure 1; and

Figure 5 is a transverse vertical section taken through the device shown in Figure 1 to the left of the first banding device and looking to the left in that figure.

Similar characters of reference indicate corresponding parts.

Referring to the drawings, and more particularly to Fig. 1, the cigars which are to be provided with a wrapper or two, or with a band, are arranged in a row side by side upon a supply conveyor belt 1, until the end cigar is blocked by a hook-shaped end 2 of a lever 3. This lever 3 is an elbow lever freely pivoted upon the axis 4. This axis or shaft 4 carries also the driving roll 5 of the conveyor belt 1. The free end of the elbow lever 3 is provided with a roller 6 which presses against a cam 8 upon the shaft 9, such pressure being brought about by the spring 7 having one end fixed to some suitable part of the frame of the machine and having the other end secured to the lever 3, so as to pull it downwards and in consequence press its roller 6 against the cam 8. The shaft 9 is driven by means of a belt or the like from the principal driving shaft 10. To the driving shaft 9, another cam 11 is keyed and this cam is acted upon by a roller 13, supported on a forked shaft follower 12' to which is connected an upright governing rod 12. The upper end of the rod 12 connects by means of a stud 14 pivotally with a lever 15, which lever 15 is in turn pivoted at 16 to a block of the frame of the machine. A spring 17 having one end secured to the frame of the machine and the other end applied to the forked end of the rod 12, serves to press the roller 13 against its cam 11. The free end of the lever 15 is provided with a friction layer 18 made of rubber or the like, which presses, upon the proper positioning of the lever 15, upon the cigar resting upon a guide table 19, after having been placed thereon by the action of the conveyor belt 1. This positioning of the lever 15 is brought about by the descent of the rod 12. The friction layer 18 of the lever 15 rests upon the end cigars of the row fed by the conveyor, but allows the end cigar abutting the hook-shaped member 2 to be entirely free.

Upon the governing rod 12 there is arranged a brake member 20 which with the lowering of lever 15 following the descent of rod 12, rests upon a brake disc 21 secured to the shaft 9, whereby upon a suitable force of the member 20 being applied to the disc, a stopping of shaft 9 is brought about. The shaft 9 is connected by some suitable means such as a gearing with the shaft 4, and in consequence the stoppage of shaft 9 brings about the stoppage of shaft 4. In view thereof, during this time there is no forward feeding of the cigars into the machine.

Upon the rotation of the shafts 9 and 4, the lever 3 with its hook-shaped portion 2 descends and permits the free end cigar abutting thereagainst to be freely moved into the machine to be there supplied with a wrapper or two, or band, if preferred.

For this purpose, reference is now made to Fig. 2. The guide table 19 which supports the end cigar, is provided with slots or openings 19' and within the slots 19' there are disposed two

oppositely directed angular holders 22, preferably provided with lateral openings, and with a sponge rubber filler 91, the filler 91 being permitted to pass out of the opening of holder 22 which permits the end of the cigar to be very softly held, so as not to injure the same in its travel and conveyance by the holders 22. These holders 22 are supported on levers 23 and 24, which are fastened to the axes 25 and 26 which axes are journaled in a carrier 27. Upon axis 25 is fixed a lever 28 and upon the axis 26 is fixed a lever 29. These levers 28 and 29 are connected by a lever 30, which is suitably adjustable by any well-known means, not shown. Upon the axis 25 is secured an additional lever 31, connected at its free end to a governing rod 32. The rod 32 has a forked end 32' which surrounds the shaft 10 and is provided with a roller 33, which cooperates with a cam 34 fixed to the shaft 10. A spring 35 fixed at one end to a suitable part of the frame 15 of the machine and at its other end to the rod 32, or on a stud thereof, serves to press the roller 33 against cam 34. The rotation of cam 34 moves rod 32 up or down and the forked end 32' of rod 32 is so arranged that it permits such action. 25

Carrier 27 is movable upon horizontal and parallel rods 36, which are mounted in a movable arm 37. Upon arm 37 which is used as a shifter, there is a stud 38 which is surrounded by the forked end 39' of a lever 39. Lever 39 is rotatably journaled at 40 to the frame of the machine and coacts by a roller 41 with a cam 42, the roller being supported on the lever 39. When the cigar holders 22 are spread apart by the action of the cam 34 operating through the roller 33 and the rod 32, the carrier 27 which supports the holders 22 is moved longitudinally of the machine by the cam 42 which acts through the roller 41 and the rod 39. This action of the cigar holders 22 produces the step-by-step advancement of cigars 40 through the banding machine in a manner which is apparent.

By this coaction of parts the end cigar is then gripped at its ends and carried into the machine itself, until it is released from the holders 22. 45

Referring again to Fig. 1, it will be seen that two wrapper folding members, generally designated by A and B are shown, above and beyond the table 1. Each of these devices consists of two arms 43 which by means of a stud 44 are connected with the levers 45 and 46. These levers 45 and 46 are seated at their other ends upon a common axis 47. A lever 55 is connected at one end with the lever 45, and at the other end with a common shift rod 56. At one end of the shift rod 56 there is connected at 57 a lever 58, which is journaled at 59 in a bearing on the frame of the machine. The lowermost end of the lever 58 is provided with a roller 60, which cooperates with a rotating cam 61 60 fixed to the shaft 65. The movement of the rod 56 in the direction of the arrow causes the lever 55 to be moved from full to dotted lines, and in consequence the movement of levers 45 and 43.

On the lower ends of the levers 43, folding fingers 48 are adjustably fastened which carry at their ends, rollers 49. Below the lower ends of the levers 43 is placed a band 50, the ends of which have secured thereto ends of springs 51 which have their other ends secured to studs 70 51' on the levers 43. Upon each of the levers 43 is also journaled a roller 52, which cooperates with a cam 53 journaled in turn upon the axis 54 supported by the frame of the machine.

Each lever 46 is provided with a lever 62, which 75

levers 62 are connected with each other by rod 63. The end of the rod 63 is connected at 64 to the lever 58. Lever 58 is pivoted at 59 and is operated by having its lowermost end cooperate with a cam 61 secured to the shaft 65. When the rod 63 is moved by the lever 58 in the direction of the arrow each lever 62 is moved from its full line position to its dotted line position. Thereby lever 46 moves lever 43 downwardly. As rod 56 when moved in the direction of its arrow, moves lever 55 from full line position to dotted line position, lever 45 and hence lever 43 were lowered.

The shaft 65 has two further cams 72 and 73 against which rollers operate, which rollers are on the lower ends of rods 70 and 71 each pivoted in the journal 59, and the upper ends of these rods are connected at 68 and 69 with the ends of horizontal shift rods 66, 67, which have their other ends secured to lower parts cams 53. At the proper time these shift rods 66 and 67 operate the cams 53 in opposite direction to each other. This operation of the cams 53 against the rollers 52, serves to move the members 48 on the lower part of the levers 43 outwardly away from each other.

Each wrapper device A and B has cooperatively related thereto, a container 74 which holds wrappers of the proper size one on top of the other. A side view of this structure is shown in Fig. 2. The container 74 is open at its bottom save for a few holding tabs. The bottom is open to permit a suction member 75 to act upon the lowermost strip. The suction member 75 seats upon a two-armed lever 76 which at 71 is journaled to a two-armed lever 78. The lever 78 is rotatably journaled in the frame of the machine by means of stud 79. On the free end of the lever 78 there is applied a roller 80 which engages a curved cam slot 81, upon the drum 82 secured to the shaft 10.

A guide rod 84 is connected at 83 to the free end of the lever 76, and the other end of the guide rod 84 is connected at 85 to the lever arm 86. This lever arm 86 is freely movable or rotatable on the shaft or stud 79 and is connected with a lever 87 which has a roller 88 at its free end. Roller 88 operates upon a cam 89 secured to the shaft 10. A spring 90 secured at one end to the lever 84 and at its other end to the lever 78, as shown, serves to press the roller 88 to the cam curve 89. By the roller operating in the curved slot or cam 81 of the drum 82, lever 78 is moved from its full line position to its dotted line position, as shown in Fig. 2, and the suction member 75 with its wrapper held thereon is thereby moved over to the cigar held between the holders 22, after the cigar has been moved inwardly of the machine. The cams 42, 34, 81 and 89 are arranged to act in proper timing in respect to the object sought to be accomplished.

The operation of the device is as follows:

As soon as the cigar which is innermost of the row of cigars lying side by side on the conveyer 1, abuts against the hook-shaped end 2 of the lever 3 (Fig. 1), the cam 11 causes the friction layer 18 of the lever 15 to press upon the next three cigars, and at the same time the conveyer belt is brought to a standstill by means of the braking devices 20 and 21. Thereupon, the cam 34 moves the levers 23, 24 in opposite directions, whereby holders 22 close in upon themselves and enclose the innermost cigar which is free from the friction layer 18. At the same time, lever 3 is moved by means of cam 8 in such a way that

the hook-shaped end 2 passes below the surface of the platform or runway 19. During the time that the cigar is held by the holders 22, the carrier 27 which is formed as a shifter, receives from cam 42 a forward movement into the machine, 5 and this is to the extent until the cigar held by the holders 22 is brought to the position shown by x in Fig. 1. During this shifting of the carrier 22, the suction member 75 has taken from the conveyer 74 a wrapper and has placed it 10 upon the cigar in its position x (Fig. 4), as there shown. The cigars in Fig. 1 are shown as squares. Before the suction member is guided back again to its starting position, the rods 58, 56, and 63 are operated by the cam 61, and the 15 levers 43 are lowered in such a manner that the folding fingers 48 place themselves upon the cigar at the same time, the band 50 presses the wrapper upon the cigar and holds it tight in that position, while the suction member returns to its 20 initial position to take on another wrapper. Of course, instead of a wrapper, a cigar band or in some countries, a custom house or tax band may be applied. By the further lowering of the levers 43 downwardly the ends of the wrapper beyond 25 the cigar are pressed downwardly by means of the folding fingers 48. If the ends of the wrapper are desired to be provided with adhesive, this may be done by means well known. After the folding fingers have crossed the underside of the 30 cigar, the rod 66 is moved by means of the lever 70 towards the right in the sense of Fig. 1. Thereby results such a movement of the left governing cam 53, that the finger on the left hand governing lever 43 is moved towards the right, 35 and thereby moves the corresponding downwardly extending tab of the wrapper around the cigar. Immediately thereafter the rod 67 is moved by lever 71 in such a way, that the other end of the wrapper is moved around the cigar 40 and upon the first applied tab of the wrapper. As soon as the wrapper is thus wrapped around the cigar by means of the folding fingers 48, and with one part of the wrapper over the other, a presser 92 comes into action to press the super- 45 posed parts together. Preferably this presser 92 has a rubber layer.

It is to be noted that as soon as the fingers 48, 48 respectively, the band 50, contact with the wrapper on the cigar whereby the cigar is 50 pressed upon the guide runway or conveyer 19, the levers 23, 24 receive such movement that they are moved away from each other, thereby the ends of the cigar are freed from the holder 22 or the sponge rubber 91 therein. Thereupon the 55 carrier 27 is returned to its initial position by the cam 42 and is then made ready to grip another cigar and move it forwardly. As soon as carrier 27 reaches this initial position, levers 23 and 24 are again moved towards each other as before 60 described. At the same time the cigar with its wrapper at x is gripped by holders 22 with the rubber 91 thus causing the overlapped ends of the band or wrapper to become firmly attached together. It is understood that some common 65 adhesive is applied to these ends and this pressure serves to bind the adhesive joint. Before the carrier 27 is placed into operation anew by means of the cam 42, whereby again the step by step displacement of the holders 22 towards the 70 right in the sense of Fig. 1 results, the lever 3 is moved or steered downwardly and the hooked end 2 moved down to free the cigar adjacent thereto. At the end of this movement, the cigar with its wrapper is moved from position x to 75

position *y*, while the cigar which at the same time abuts against end 2 is moved to the position *x*. While the operation before described repeats itself in respect to the cigar now at *x*, the wrapped cigar now at *y* is gripped by two scissor-like pressers 93, over the surrounding wrapper, whereby the cigar is held fast, and at the same time a pressure is exerted upon that part of the wrapper which has the adhesive. During such holding, the holders 22 are freed from the cigar and the carrier 27 can again return to its initial position. During this time a third cigar abuts against the hook-shaped end 2. The operation repeats itself for this third cigar. But the first treated or wrapped cigar is brought from position *y* to position *y'* where two press members 93 grip the cigar over its wrapper again and press it. Thereupon, the separation of the holders 22 again takes place. The cigar then is moved by the holders 22 from the position *y'* to the position *y''* and again it is pressed by the press members 93. These three press members 93 are joined together by a common mechanism so as to operate in unison against different cigars in various stages of completion in respect to their wrappers.

It is clear that the cigars by every tour of the machine, are advanced one step further, whereby the cigar before the hook-shaped part 2 is step by step advanced and surrounded in its course of movement by a wrapper through the action of device A.

From the position of *y''*, the cigar reaches the position *z*, and is within the zone of operation of device B. Here a pneumatic suction member 74 having a wrapper contacting end 75 draws out of the container another kind of wrapper and by the operation of device B, this wrapper is applied to the cigar having already one wrapper applied thereto. Finally, the cigar is deposited complete in the row 94.

It is obvious that various changes and modifications may be made in the details of construction and design of the above specifically described embodiment of this invention without departing from the spirit thereof, such changes and modifications being restricted only by the scope of the following claims.

I claim:

1. In a cigar wrapping machine, a cigar wrapping device consisting of a support, levers pivoted upon said support, an arm pivoted to each of said levers, folding fingers on the free ends of the arms, rollers on the arms intermediate their ends, cam devices suitably supported and adapted to cooperate with said rollers, means biasing said arms towards one another, means for operating said cam devices whereby the fingers on the arms are adapted to overlap the ends of a wrapper about the cigar, a pressure band trained across said fingers and interposed between the fingers and the wrapper, and resilient means for supporting said pressure band.

2. A cigar wrapping device comprising a pair of arms, a pair of inturned fingers mounted respectively one on each of the said arms, a pressure band trained across said fingers, means for

moving said arms towards a cigar whereby the adjacent ends of the said fingers draw said band down on opposite sides of the cigar, and means for swinging said arms independently to pass said fingers across the underside of the cigar one 5 after the other.

3. A cigar wrapping device comprising a pair of arms, inturned fingers mounted one on each of said arms, means for moving said arms simultaneously towards a cigar, means associated with 10 each arm for maintaining said arms in spaced relation to permit the adjacent ends of said fingers to pass on opposite sides of a cigar, means for moving said arms independently to cause the said fingers to move across the underside of the cigar 15 one after the other, a pressure band trained across said fingers and interposed between the fingers and the wrapper, and resilient means for supporting said pressure band.

4. A cigar wrapping machine comprising a pair 20 of pivoted arms, a pair of inturned fingers mounted one on each of said arms, means biasing said arms towards one another, means for moving said arms towards a cigar, spacing means for holding said arms in spaced relation whereby 25 the adjacent ends of said fingers pass on opposite sides of the cigar, means for independently moving said spacing means to permit said arms to move one after the other to pass said fingers across said cigar, and a resiliently acting pres- 30 sure band trained across and over said fingers.

5. In a cigar wrapping machine, a table, means for moving a cigar on said table longitudinally thereof, a cigar wrapping device positioned above said table, means for supplying a wrapper below 35 said cigar wrapping device, said cigar wrapping device consisting of levers suitably operated to swing into position, guide finger levers pivoted to each lowermost end of said levers, and having rollers thereon to move the wrapper around a 40 cigar placed upon the table by the movement of said levers, and a pressure band resiliently trained across the lowermost ends of said levers and below said rollers of said guide finger levers and 45 interposed between the guide finger levers and rollers and the wrapper.

6. In a cigar wrapping machine a wrapper device consisting of a support, levers pivoted upon said support, an arm pivoted to each of said levers, folding finger levers on the free ends 50 of the arms extending inwardly between the arms, means for moving each of the levers and in consequence each of the arms and the folding finger levers in a swinging movement, towards and away from each other, a spring for biasing 55 the arms when the finger levers move towards one another, a pressure band trained across and over the ends of said finger levers and interposed between the finger lever ends and the wrapper, and a cigar and wrapper support, whereby the 60 finger levers on the arms move a wrapper extending beyond the cigar around the same and across the cigar to overlap the ends of the wrapper.
